US00D656192S

(12) **United States Design Patent**
Chen

(10) **Patent No.:** **US D656,192 S**
(45) **Date of Patent:** **** Mar. 20, 2012**

(54) **MARKER**

(75) Inventor: **Bei Chen**, Ningbo (CN)

(73) Assignee: **Beifa Group Co., Ltd.**, Ningbo (CN)

(**) Term: **14 Years**

(21) Appl. No.: **29/384,492**

(22) Filed: **Jan. 31, 2011**

(30) **Foreign Application Priority Data**

Aug. 4, 2010 (CN) 2010 3 0266939

(51) **LOC (9) Cl.** **19-06**

(52) **U.S. Cl.** **D19/41**

(58) **Field of Classification Search** ..... D19/35, D19/36, 41-51, 54-58; D14/411, 431; 24/11 R, 24/11 F, 11 P; 401/52, 99, 100, 104-109, 401/192, 195, 196; D28/88, 89, 90

(57) **CLAIM**

The ornamental design for a marker, as shown and described.

DESCRIPTION

FIG. 1 is an upper front right perspective view of a marker showing my new design;

FIG. 2 is a front elevation view thereof;

FIG. 3 is a rear elevation view thereof;

FIG. 4 is a right side elevation view thereof, with the left side elevation view being a mirror image of the right side elevation view; and,

FIG. 5 is an enlarged bottom plan view thereof, with the top plan view being a mirror image of the bottom plan view.

1 Claim, 3 Drawing Sheets

Fig.1.

Fig. 2.

Fig. 3.
